UNITED STATES PATENT OFFICE

101,813

DESIGN FOR A TEXTILE FABRIC

August Hafner, Flushing, N. Y.

Application June 5, 1936, Serial No. 63,046

Term of patent 3½ years

To whom it may concern:

Be it known that I, August Hafner, a citizen of the United States of America, residing at Flushing, county of Queens, and State of New York, have invented a new, original, and ornamental Design for a Textile Fabric, of which the following is a specification, reference being had to the accompanying drawing, forming part hereof, wherein—

The figure is a plan view of a textile fabric showing my new design.

I claim:

The ornamental design for a textile fabric substantially as shown.

AUGUST HAFNER.
